VACUUM CLEANER

Robert Lay Hallock, Larchmont, N. Y.

Application September 20, 1944, Serial No. 554,879

24 Claims. (Cl. 183—54)

1

My invention relates to vacuum cleaners and more particularly to vacuum cleaners of the type wherein the motor-fan unit and the means for separating dust from the air are contained within a casing which is connected to the nozzle or other cleaning implement by means of a flexible hose.

In accordance with my invention, the dust separating member or primary filter is permanently secured within the casing and the dust separated from the air thereby is collected in a removable impervious container, such as a drawer. While a large percentage of the dirt will be deposited directly in the drawer, a certain amount thereof will adhere to the filter, even after the flow of air has ceased. Consequently, it is highly desirable to provide means for removing this dirt from the filter from time to time, and in accordance with my invention, I provide mechanism which automatically shakes the filter every time the motor is stopped.

The energy for shaking the filter is obtained from the inertia of the motor after the electric current has been interrupted, which energy otherwise would be dissipated. Inasmuch as the fan would normally continue to produce flow of air during the slowing down period after the current has been shut off, I provide valve means automatically operable in response to the interruption of the current for preventing flow of air through the filter while the latter is being shaken. Thus, there is no tendency resulting from air flow for the dust to adhere to the filter, or to be carried back to the filter during the shaking operation.

A further object of my invention is to provide an improved means for guiding the air in the neighborhood of the filter so that the heavier particles of dirt are thrown away from the filter and are deposited in a dirt receptacle, while only the finest particles are carried by the air to, and deposited on, the filter.

Another object of my invention is to provide an improved dust drawer arrangement, including means for sealing the drawer with respect to the casing while permitting convenient removal and insertion of the drawer.

Further objects and advantages of my invention will be apparent from the following description considered in connection with the accompanying drawings, which form a part of this specification and of which:

Fig. 1 is a cross-sectional view of a preferred embodiment of my invention;

Fig. 2 is a cross-sectional view of a portion of

2

the device shown in Fig. 1, but drawn on a larger scale and showing certain of the parts in a different position;

Fig. 3 is a top view of the device shown in Fig. 1, partially broken away to show certain interior construction; and

Fig. 4 is a wiring diagram showing the electrical connections.

Referring to the drawings, reference character 10 designates generally a casing of a vacuum cleaner. The casing includes a base portion 12, an intermediate cylindrical portion 14 permanently secured to the base portion and an upper cylindrical portion 16 removably secured to the intermediate portion. The base portion 12 is formed with a flat bottom 18 which is adapted to rest on a floor or other suitable horizontal supporting surface. The base portion is generally rectangular in shape, but is formed with an opening 20 through which may be inserted and removed a dust drawer 22.

The front of the drawer carries a plate 24 which substantially closes the opening 20, but does not necessarily make an airtight seal. A handle member 26 is rigidly secured to the plate 24. The width of the drawer 22 is somewhat less than the interior width of the base 12 and a lever 28 is pivotally mounted on a pin 30 on each side of the exterior of the drawer. Each of these levers 28 extends out beyond the plate 24, where they are joined to a handle 32. A spring 34 is connected between each lever 28 and the side of the drawer and tends to pivot the lever in a counterclockwise direction, as viewed in Fig. 1. An abutment 36 is provided on the inner side wall of the base portion 12 on each side of the drawer in such a position as to be contacted by the inner end of the lever 28 when the drawer is in place.

The upper edge of the drawer is preferably formed with a bead 38 which is adapted to make sealing contact with a gasket 40 carried by the top wall 42 of the base portion.

The intermediate portion 14 is suitably secured within a circular opening formed in the top wall 42. The lower part of the intermediate portion is surrounded by a wall 44 having a frustoconical shape, the upper edge of the wall 44 being secured to the cylindrical portion 14, while the lower edge is secured to the top wall 42. The wall 44 is formed with an opening in which is located a coupling member 46 to which may be connected a suitable hose leading to a nozzle or other suction cleaning implement. As is shown more clearly in Fig. 3, the lower part of the cylindrical portion 14 within the wall 44 is cut

away for about one quarter of its peripheral extent to provide an opening 48 for establishing communication from the space 50 formed between the cylindrical portion and the wall 44 to the space within the cylindrical portion. A curved wall 52 is disposed opposite the opening 48 and extends from the conical wall 44 to the cylindrical portion 14, as is clearly shown in Fig. 3.

The upper end of the cylindrical portion 14 is provided with a gasket 54 which provides an airtight seal with the upper portion 16. Secured to the bottom of the cylindrical portion 16 is a ring 56 which carries a plurality of peripherally spaced blocks 58 made of rubber or other suitable vibration absorbing material. Suspended within the ring 56 by means of these blocks is a motor-fan unit designated generally by reference character 60. This unit includes a fan housing 62 to the lower end of which is secured an electric motor 64. The upper end of the armature shaft 66 of the motor carries one or more stages of fan blading 68. The top wall 70 of the fan housing is perforated so as to permit discharge of air from the fan to within the upper portion 16.

Secured around the ring 56 is a dust separating member or primary filter 72 which has the general shape of a cylindrical bag. A plurality of substantially rigid strips 74 depend from the ring 56 in order to space the side of the bag 72 from the fan housing 62.

Located within the bottom of the bag-shaped dust separator 72 is a perforated dished disc 76, the outer edge of which preferably carries a gasket 76 which engages the material of the bag. The central portion of disc 76 is formed as an opening surrounded by a conical wall 80. As shown in Fig. 1, this wall rests on the exterior conical surface of an outer ball race 82. The inner race 84 is eccentrically mounted on the lower end of the armature shaft 66. The eccentric bearing is counterbalanced by means of eccentrically located weights 86, whereby the shaft as a whole is dynamically balanced. A plurality of resilient arms 88 are carried by the motor housing and contact the upper surface of disc 76 to thereby urge the wall 80 into engagement with the outer bearing race 82. An imperforate cap 90 is secured to the lower side of disc 76 underneath the opening therein so as to collect any oil or grease which might drop from the lower end of the armature shaft, thereby preventing it from reaching the filter. The lower end of the motor housing is formed with a plurality of openings 92 through which air passes to the inlet of the fan housing 62, thus assuring adequate cooling of the motor.

The upper portion 16 is formed with a lower wall 94 in which is formed an opening 96. Mounted on the top wall 70 of the fan housing in alignment with the opening 96 is a solenoid 98, the armature 100 of which carries a bell shaped valve member 102. The lower flared skirt of this valve member is adapted to cooperate with a gasket 104 which surrounds the opening 96 to prevent flow of air through the opening.

An intermediate wall 106 extends across the cylindrical portion 16, above which wall may be located a cord reel for the electric cord 108, but as such reel forms no part of the present invention, it is not illustrated. The side wall of upper portion 16 may be formed with an opening communicating with the space between walls 94 and 106, through which opening may be inserted and removed a secondary or fine filter

110, through which air which enters from the opening 96 must pass on its way to an exhaust opening 112. As shown, a plurality of air guide vanes 114 are arranged across this opening and preferably form part of a gate pivoted at 116 so that they may be swung inwardly to permit the insertion of a hose in the opening 112 if it is desired to use the cleaner for blowing.

Secured to the under side of the wall 106 above the solenoid 98 is a circuit breaker which includes a pair of contact carrying arms 120 and 122. Arm 122 is resilient and is formed with a hook shaped end 124 which extends between the arm 120 and the upper end of the armature 100 of the solenoid so that, when the latter is raised it contacts the end 124 and deflects the arm 122 upwardly to thereby open the circuit.

The top of portion 16 is provided with a suitable carrying handle 126, together with a suitable step switch 128 for manually controlling the supply of electric current from the cord 108 to the motor 64.

A suction relief valve is preferably provided in the wall of intermediate portion 14. As shown in Fig. 1, the wall is formed with an opening 130 covered by a perforated cap 132 which is secured to the wall. This cap carries a spindle 134 on which is slidably mounted a valve member 136 provided with a suitable gasket for sealing against the interior of the wall. A spring 138 is compressed between the valve member and a nut or other suitable abutment 140 on the inner end of spindle 134 and urges the valve to closed position.

Fig. 4 is a wiring diagram showing the electric circuit of the parts already described. As here shown, the coil of solenoid 98 is connected in parallel with the motor 64 so as to be energized whenever the motor is supplied with current. The step switch 128 and the circuit breaker actuated by the armature 100 of the solenoid are each connected between the motor and the cord 108, whereby opening of either the switch or the circuit breaker interrupts the flow of current to both the motor and the solenoid coil.

The above-described device operates as follows:

In Fig. 1 the various parts are shown in the positions which they occupy when the motor 64 is not operating. Thus, the disc 76 is urged downwardly, both by gravity and the force of resilient arms 88 so that conical portion 80 is in engagement with the outer ball race 82, and armature 100 is in its lower position where it is held by gravity and consequently valve member 102 is in a position to permit flow of air through opening 96.

If the cord 108 is plugged in to a suitable source of current and the step switch 128 is closed, current is supplied to both the motor and to the coil of solenoid 98. The latter is thus energized so as to hold the armature thereof in its lowermost position. The supply of current to the motor causes the armature shaft 66 thereof to rotate and the eccentrically mounted ball bearing at the lower end of the shaft imparts a circular oscillating movement to the disc 76. However, as soon as the motor starts, the fan blading 68 creates a flow of air inwardly through the coupling 46 from the hose attached thereto, and this air must pass through the primary filter 72 to reach the inlet of the fan. The filter offers an appreciable resistance to the flow of the air and consequently a lower pressure exists within the filter than within the space between the filter and the casing 14. This causes that portion of the filter between the lower ends of the support 74 and the disc 76 to be drawn inwardly towards the motor, thus

raising the lower end of the filter and the disc 76 against the action of the resilient arms 88. This lifts the conical wall 80 off the outer race 82 to the position shown in Fig. 2. Consequently, the disc 76, which constitutes the shaking member for the filter is not moved by the eccentric ball bearing.

Dust laden air which enters through the coupling 46 flows to the left, as shown in Fig. 3, through the space 50 and thence through the opening 48 to the interior of the cylindrical portion 14. As it passes through the opening 48 centrifugal force keeps the heavier particles away from the filter and as the velocity decreases the heavier particles of dirt are precipitated to within the dust drawer 22 without having adhered to the filter. The lighter particles are carried with the air to the filter 72, the air passing through the filter, while the dirt adheres to the outer surface thereof. The air which is passed through the filter continues through the openings 92 and around the motor windings and thence to the inlet of the fan housing 62. From the fan, the air is discharged through the perforated plate 70 and flows through the opening 96. The flow of air through this opening tends to lift the bell shaped valve member 102, but the solenoid prevents such movement of the valve member. After flowing through the opening 96 the air passes through the secondary or fine filter 110 and thence through the exhaust opening 112 to the atmosphere.

When the step switch 128 is again operated to interrupt the flow of current to the motor 64, it also deenergizes solenoid 98. This permits the air to immediately lift the valve member 102, thus stopping flow of air through the cleaner. This causes a rapid equalization of air pressure on either side of the primary filter 72, thus permitting the resilient arms 88 to force the disc 76 downwardly to bring the conical wall 80 into engagement with the outer race 82 of the eccentric ball bearing. Even though the supply of current to the motor has been interrupted, the armature thereof is still rotating rapidly and has sufficient inertia to continue to rotate for several seconds while the shaking member 76 is engaged with the ball bearing. As previously stated, this imparts to the member 76 a rapid rotary oscillating motion which vigorously shakes the filter 72. Inasmuch as there is no flow of air through the filter at this time, the dust which previously has been adhering thereto is shaken loose and settles into the dust drawer 22.

It will be noted that this shaking takes place every time the motor is shut off and hence it is not necessary to rely on the operator remembering to shake the bag periodically.

The circuit breaker is provided as a safety feature to eliminate any possibility of the filter being continuously shaken if, after the switch 128 has been opened, it were closed almost immediately and before the motor had stopped coasting. As above described, opening of the switch 128 deenergizes the solenoid, thus permitting the air to lift the valve member 102. However, if the motor were again started while the valve member were so lifted, the accompanying energization of the solenoid might not produce sufficient magnetic force to pull the valve open against the force of the air. If this were to occur, the filter shaking member 76 would remain in engagement with the eccentric ball bearing because there would be no flow of air to distort the filter, and the latter would be shaken as long as the motor continued

to operate. This would result in unnecessary wear on the parts, particularly on the regular motor bearings, especially since the motor would be operating at substantially full speed, whereas normally it is slowing down while the shaking takes place. The circuit breaker prevents the possibility of such an occurrence, inasmuch as raising of the valve member 102 automatically lifts the arm 122 and hence maintains the circuit open at this point as long as the valve is closed. Consequently, even if the step switch 128 were closed, the motor would not start until it had slowed down sufficiently so that the air flow produced by the fan would not be enough to hold the valve member 102 up.

The suction relief valve 136 is provided to prevent the possibility of the filter being continuously shaken if the flow of air were interrupted by any obstruction in the inlet, such as might occur if the operator placed her hand over the end of the hose or if the latter became badly clogged with dirt. Such interruption causes the pressure within the intermediate portion 14 to drop and consequently atmosphere pressure acting on valve 136 opens the latter against the force of spring 138, thus permitting sufficient air flow to take place to maintain the filter in displaced position, which in turn holds the shaking member out of engagement with the eccentric. The strength of spring 138 is so chosen as to keep the valve 136 closed during normal operation, but to permit the valve to open before the pressure in the intermediate portion falls to such a low value that the shaking member would engage the eccentric.

When it is desired to empty the dust drawer, it may be removed by pivoting the lever 28 in a clockwise direction as viewed in Fig. 1. This may be done conveniently by placing the fingers under the rigid handle 26 with the thumb on the handle 32 and moving the latter downward. This permits the drawer to drop away from the gasket 40 and hence the drawer may be withdrawn through the opening 20 and emptied. In order to replace the drawer, the handle 32 is again moved towards the handle 26 and the drawer inserted through the opening 20. When the drawer is in place, the handle 32 is released, whereupon the springs 34 pivot it in a counter-clockwise direction, thus causing the inner ends of the levers 28 to bear against the abutments 36 and to thus lift the drawer into contact with the gasket 40. During operation, the interior of the drawer is maintained at a sub-atmospheric pressure, and consequently atmospheric pressure acting on the bottom of the drawer aids the springs in maintaining a tight seal between the top of the drawer and the gasket 40.

While I have shown one more or less specific embodiment of my invention, it is to be understood that this has been done for the purpose of illustration only and that the scope of my invention is not to be limited thereto, but is to be determined from the appended claims.

What I claim is:

1. In a vacuum cleaner, a filter, a fan for producing flow of air through said filter, a motor for operating said fan, means for supplying power to said motor, means for interrupting the supply of power to said motor, means for stopping flow of air through said filter when the supply of power is interrupted and while the motor is still rotating and means automatically operative by the motor to shake said filter while the flow of

air is stopped and while the motor is still rotating.

2. In a vacuum cleaner, a filter, a fan for producing flow of air through said filter, an electric motor for operating said fan, a switch for controlling the supply of current to said motor, valve means operable in response to opening of said switch for interrupting flow of air through said filter, and means automatically operative in response to operation of said valve means to shake said filter while the flow of air is interrupted.

3. In a vacuum cleaner, a filter, a fan for producing flow of air through said filter, a motor for operating said fan, means for supplying power to said motor, means for interrupting the supply of power to said motor, means for stopping flow of air through said filter substantially immediately upon the interruption of said supply of power, and means operative in response to the stopping of flow of air through the filter for utilizing the inertia of the moving parts of said motor for shaking said filter when said supply of power is interrupted.

4. In a vacuum cleaner, a filter, a fan for producing flow of air through said filter, an electric motor for operating said fan, a switch for controlling the supply of current to said motor, valve means operable in response to opening of said switch for interrupting flow of air through said filter, and means operative by the inertia of the armature of said motor in response to the stopping of air flow through the filter for shaking said filter.

5. In a vacuum cleaner, a filter, a fan for producing flow of air through said filter, a motor for operating said fan, means for supplying power to said motor, means for interrupting the supply of power to said motor, means for stopping flow of air through said filter substantially immediately upon the interruption of said supply of power, an eccentric driven by said motor, a shaking member associated with said filter, and means operative in response to the interruption of the flow of air through the filter for engaging said shaking member with said eccentric.

6. In a vacuum cleaner, a filter, a fan for producing flow of air through said filter, an electric motor for operating said fan, a switch for controlling the supply of current to said motor, valve means operable in response to opening of said switch for interrupting flow of air through said filter, an eccentric driven by said motor, a shaking member associated with said filter, and means operative in response to the closing of said valve for engaging said shaking member with said eccentric.

7. In a vacuum cleaner, a filter, a fan for producing flow of air through said filter, an electric motor for operating said fan, a switch for controlling the supply of current to said motor, valve means operable in response to opening of said switch for interrupting flow of air through said filter, an eccentric driven by said motor, a shaking member associated with said filter, and means operative in response to air flow for maintaining said shaking member out of engagement with said eccentric when said fan is producing flow of air and for engaging said member with said eccentric when the flow of air is interrupted by the closing of said valve.

8. In a vacuum cleaner, a casing, a filter, means for supporting a portion of said filter in fixed position in said casing, a fan for producing flow of air through said filter, another portion of said

filter being displaceable by the pressure difference resulting from flow of air therethrough, an electric motor for operating said fan, a switch for controlling the supply of current to said motor, valve means operable in response to opening of said switch for interrupting flow of air through said filter, an eccentric driven by said motor, and a shaking member connected to the displaceable portion of said filter, said member being held out of engagement with said eccentric when said filter is displaced due to flow of air therethrough and engaging said eccentric when the flow of air is interrupted by the closing of said valve.

9. In a vacuum cleaner, a casing, a tubular filter, means for supporting the upper end of said filter in fixed position in said casing, a fan for producing flow of air through said filter, the lower end of said filter being displaceable vertically by the pressure difference resulting from flow of air through the filter, an electric motor for operating said fan, a switch for controlling the supply of current to said motor, valve means operable in response to opening of said switch for interrupting flow of air through said filter, an eccentric driven by said motor, and a shaking member connected to the lower end of said filter, said member being held out of engagement with said eccentric when the lower end of said filter is displaced upwardly due to flow of air through the filter and engaging said eccentric when the flow of air is interrupted by the closing of said valve.

10. In a vacuum cleaner, a casing, a tubular filter, means for supporting the upper end of said filter in fixed position in said casing, resilient means for urging the lower end of said filter downwardly, a fan for producing flow of air through said filter, the lower end of said filter being displaceable upwardly against the action of said resilient means by the pressure difference resulting from flow of air through the filter, an electric motor for operating said fan, a switch for controlling the supply of current to said motor, valve means operable in response to opening of said switch for interrupting flow of air through said filter, an eccentric driven by said motor, and a shaking member connected to the lower end of said filter, said member being held out of engagement with said eccentric when the lower end of said filter is displaced upwardly due to flow of air through the filter and engaging said eccentric under the influence of said resilient means when the flow of air is interrupted by the closing of said valve.

11. In a vacuum cleaner, a casing, a tubular filter, means for supporting the upper end of said filter in fixed position in said casing, a fan for producing flow of air through said filter, the lower end of said filter being displaceable vertically by the pressure difference resulting from flow of air through the filter, an electric motor for operating said fan, a switch for controlling the supply of current to said motor, valve means operable in response to opening of said switch for interrupting flow of air through said filter, a ball bearing having an inner race and an outer race, means for mounting said inner race eccentrically on the shaft of said motor, and a shaking member connected to the lower end of said filter, said member being held out of engagement with said outer race when the lower end of said filter is displaced upwardly due to flow of air through the filter and engaging said outer race

when the air flow is interrupted by the closing of said valve.

12. In a vacuum cleaner, a filter, a fan for producing flow of air through said filter, an electric motor for operating said fan, a manually operable switch for controlling the supply of current to said motor, valve means operable in response to opening of said switch for interrupting flow of air through said filter, an eccentric driven by said motor, a shaking member associated with said filter, means operative upon the interruption of the flow of air through the filter for engaging said shaking member with said eccentric, and a second switch in series with said manually operable switch arranged to be opened automatically by the closing of said valve.

13. In a vacuum cleaner, a filter, a fan for producing flow of air through said filter, an electric motor for operating said fan, a switch for controlling the supply of current to said motor, valve means operable in response to opening of said switch for interrupting flow of air through said filter, an eccentric driven by said motor, a shaking member associated with said filter, means operative in response to air flow for maintaining said shaking member out of engagement with said eccentric when said fan is producing flow of air and for engaging said member with said eccentric when the flow of air is interrupted by the closing of said valve, and a second switch in series with said manually operable switch arranged to be opened automatically by the closing of said valve.

14. In a vacuum cleaner, a casing, an electric motor mounted within said casing with the shaft thereof extending in substantially a vertical direction, a fan at one end of said motor, a tubular filter surrounding said motor and fan, means for supporting the upper end of said filter in fixed position in said casing, the lower end of said filter being displaceable vertically by the pressure difference resulting from flow of air produced by the fan through the filter, a switch for controlling the supply of current to said motor, valve means operable in response to opening of said switch for interrupting flow of air through said filter, an eccentric driven by the lower end of said motor shaft, a shaking member connected to the lower end of said filter, said member being held out of engagement with said eccentric when the lower end of said filter is displaced upwardly due to flow of air through the filter and engaging said eccentric when the flow of air is interrupted by the closing of said valve.

15. In a vacuum cleaner, a casing having an inlet and an outlet, a tubular filter, means for supporting the upper end of said filter in fixed position in said casing with space between the tubular side of the filter and the casing, a fan for producing flow of air from said inlet through said filter, air guide means for directing the air into said space tangentially with respect to said filter, the lower end of said filter being displaceable vertically by the pressure difference resulting from flow of air inwardly through said filter to said fan, an electric motor for operating said fan, a switch for controlling the supply of current to said motor, valve means disposed between said fan and said outlet and operable in response to opening of said switch for interrupting flow of air through said filter, an eccentric driven by said motor, and a shaking member connected to the lower end of said filter, said member being held out of engagement with said eccentric when the lower end of said filter is dis-

placed upwardly due to flow of air through the filter and engaging said eccentric when the flow of air is interrupted by the closing of said valve.

16. In a vacuum cleaner, a filter, a fan for producing flow of air through said filter, a motor for operating said fan, means for supplying power to said motor, means for interrupting the supply of power to said motor, means for stopping flow of air through said filter substantially immediately upon the interruption of said supply of power, an eccentric mounted on the shaft of said motor, means for counterbalancing said eccentric to dynamically balance said shaft, a shaking member associated with said filter, and means operative upon the interruption of said supply of power for engaging said shaking member with said eccentric.

17. In a vacuum cleaner, a filter, a fan for producing flow of air through said filter, an electric motor for operating said fan, a switch for controlling the supply of current to said motor, valve means disposed in the path of air flow and so arranged that the flowing air tends to close the valve, a solenoid for opening said valve and holding it open against the force of the air, said solenoid being connected so as to be deenergized by the opening of said switch, and means automatically operative to shake said filter while the flow of air is interrupted by the closing of said valve.

18. In a vacuum cleaner, a filter, a fan for producing flow of air through said filter, an electric motor for operating said fan, a switch for controlling the supply of current to said motor, valve means disposed in the path of air flow and so arranged that the flowing air tends to close the valve against the force of gravity, a solenoid for holding said valve open against the force of the air, said solenoid being connected so as to be deenergized by the opening of said switch, and means automatically operative to shake said filter while the flow of air is interrupted by the closing of said valve.

19. In a vacuum cleaner, a filter, a fan for producing flow of air through said filter, an electric motor for operating said fan, a switch for controlling the supply of current to said motor, valve means disposed in the path of air flow and so arranged that the flowing air tends to close the valve against the force of gravity, a solenoid for holding said valve open against the force of the air, said solenoid being connected so as to be deenergized by the opening of said switch, an eccentric driven by said motor, a shaking member associated with said filter, means operative upon the interruption of the flow of air through the filter by the closing of said valve for engaging said shaking member with said eccentric, and a second switch in series with the first-mentioned switch and arranged to be opened automatically by the closing of said valve.

20. In a vacuum cleaner, a casing, a tubular filter, means for supporting one end of said filter in fixed position in said casing, resilient means for urging the other end of said filter away from the first-mentioned end, a fan for producing flow of air through said filter, said other end of said filter being displaceable towards said first-mentioned end against the action of said resilient means by the pressure difference resulting from flow of air through the filter, an electric motor for operating said fan, a switch for controlling the supply of current to said motor, valve means operable in response to opening of said switch for interrupting flow of air through said filter, an eccentric driven by said motor, and a shaking

member connected to said other end of said filter, said member being held out of engagement with said eccentric when said other end of said filter is displaced towards said first-mentioned end due to flow of air through the filter and engaging said eccentric under the influence of said resilient means when the flow of air is interrupted by the closing of said valve.

21. In a vacuum cleaner, a casing having an inlet and an outlet, a filter, means for supporting a portion of said filter in fixed position in said casing, a fan for producing flow of air from said inlet through said filter, another portion of said filter being displaceable by the pressure difference resulting from flow of air therethrough, an electric motor for operating said fan, a switch for controlling the supply of current to said motor, valve means operable in response to opening of said switch for interrupting flow of air through said filter, an eccentric driven by said motor, a shaking member connected to the displaceable portion of said filter, said member being held out of engagement with said eccentric when said filter is displaced due to flow of air therethrough and engaging said eccentric when the flow of air is interrupted by the closing of said valve, and a vacuum relief valve in said casing for admitting air to said filter in the event flow through said inlet is interrupted.

22. In a vacuum cleaner, a casing, a flexible filter within said casing, a movable support for a portion of said filter, a motor-fan unit within said casing for drawing air through said flexible filter, a shaft for said motor-fan unit and an eccentric on the said shaft engageable with said movable support for moving said filter, said filter being operable in response to the air passing therethrough to withdraw said movable support from engagement with said eccentric.

23. In a vacuum cleaner, a filter, a fan for pro-

ducing flow of air through said filter, valve means operable to interrupt the flow of air through the filter, a shaking member operably associated with said filter, an actuator for operating said shaking member, and means responsive to the interruption of air flow resulting from operation of said valve for causing said actuator to operate said shaking member.

24. A suction cleaner comprising a casing, a fan motor unit disposed in said casing for moving air therethrough, a tubular filter movably mounted in the path of flow of air through said casing, means supporting said filter and driven by the shaft of said fan motor unit for imparting to said filter a gyratory movement about the axis of said shaft, said last-mentioned means including a gyratory element eccentrically connected to and driven by the shaft of the fan motor unit and on which said filter is movably mounted, and means for preventing rotation of said filter.
